UNITED STATES PATENT OFFICE

2,082,628

ROLLER HEARTH FURNACE

George W. Hegel, Scotia, N. Y., assignor to General Electric Company, a corporation of New York

Application August 5, 1936, Serial No. 94,380

6 Claims.

(Cl. 263—6)

My invention relates to roller hearth furnaces of the type which is adapted to contain a gas atmosphere. Furnaces of this type having a series of driven rolls extending through the furnace wall to the driving mechanism heretofore have been provided with stuffing boxes for the separate rolls to prevent the escape of the gas employed in the furnace. Where a furnace includes many driven rolls the combined friction of 10 the many stuffing boxes imposes an objectionably heavy load on the driving mechanism. It is an object of my invention to provide an improved construction of roller hearth furnace which while effective to prevent the loss of gas therefrom around the rolls avoids the necessity of employing stuffing boxes and hence reduces the load on the driving mechanism.

My invention will be better understood from the following description taken in connection with the accompanying drawings, and its scope will be pointed out in the appended claims.

Referring to the drawings, Fig. 1 is a side view of a roller hearth furnace embodying my invention; Fig. 2 is a cross-sectional view of the same taken on the line 2—2 of Fig. 1 and drawn to a larger scale; Fig. 3 is a cross-sectional view taken on the line 3—3 of Fig. 1; Fig. 4 is an enlarged plan of a detail of the furnace shown in Fig. 1; Fig. 5 is a side view partly in section of the left hand end of the gas tight casing shown in Fig. 1; Fig. 6 is a cross-sectional view taken on the line 6—6 of Fig. 5; Fig. 7 is a longitudinal sectional view taken through the central portion of Fig. 5; Fig. 8 is a detail view of the gas tight casing at the right hand end of Fig. 1; Fig. 9 is a cross-sectional view taken on the line 9—9 of Fig. 8; Fig. 10 is a longitudinal cross-sectional view through the central portion of Fig. 8; and Fig. 11 is a sectional view taken on the line 11—11 of Fig. 10.

The furnace 1 comprises the outer sheet metal casing 2 within which is a relatively thick layer 3 of heat insulating material having the lining 4 of refractory material as is usual in furnaces of this type. The heating chamber so formed is normally closed at each end of the furnace in order to retain the gas which constitutes the gas atmosphere, suitable provision being made for passing into and out of the furnace the material to be treated therein. Heat may be supplied to the heating chamber of the furnace by any desired means, the chamber in this case being represented as being heated by the several electric heating units 5.

55 The work to be heated in the furnace is sup-

ported upon a series of parallel rolls 6 which pass through suitable openings in the furnace walls on opposite sides of the heating chamber, the ends of the rolls being reduced in diameter and supported in bearings outside of the walls. The 5 bearings 7 at one side of the furnace, are secured directly and in a gas tight manner to the outer casing 2 and are constructed with closed ends thereby to avoid the necessity of using stuffing boxes to prevent the loss at those points of the 10 gas forming the atmosphere in the furnace.

At the other side of the furnace the reduced ends of the rolls are somewhat longer and on those ends suitable means are provided by which the rolls are rotated. An example of such means is 15 shown in the drawings as comprising the sprockets 9 secured to the reduced ends of the rolls and engaging with those sprockets is the endless chain 10. For producing a desired tension in the chain I have shown a well known form of tension adjusting means 11 at one end of the chain loop, see Figs. 5 and 7. At the opposite end of the loop I have shown the idler sprocket 12 and the drive sprocket 13, see Figs. 10 and 11, which through the drive shaft 14 connects with the 20 drive sprocket 15. The latter sprocket connects through the chain 16 with a sprocket on the counter shaft 17 which is driven through the chain 18 from the motor 19 through the gear reducing mechanism 20.

In order to avoid the use of stuffing boxes at those ends of the rolls at which the drive is connected I provide the furnace with the gas tight casing 22 which encloses the ends of the rolls, the sprockets thereon, and the drive chain associated therewith. This casing comprising an enclosure formed by the upper and lower plates 23 and 24 respectively, the channel 25 and the angle 26 as shown in Figs. 5, 6, and 7. It also comprises the several members 27 which are 35 detachably secured in a gas tight manner to the outer face of the channel 25 over openings therein through which the ends of the rolls extend. They serve the double purpose of forming bearings for the rolls and preventing the escape of 40 gas through the bearings. The casing thus formed is closed at one end by the end plate 28 and at the other end by the housing 29 in which is mounted the idler 12 and sprocket 13. According to this construction there is only one 45 point at which a stuffing box is required and that is at the point where the drive shaft 14 passes through the housing 29, the stuffing box at this point being represented at 30. Shaft 14 is journaled in two bearings one of which is repre- 50 55

sented at 31 within the housing 29 and the other at 32 carried by the frame 33.

The above description applies to that part of the furnace in which the articles to be treated 5 therein are heated. The furnace is shown in Fig. 1 as including also the cooling chamber 35 which is likewise provided with a series of rolls like those described above, these rolls also being mounted in a manner similar to the above-10 described rolls and having their corresponding ends enclosed by a gas tight casing shown at 36 which functions in the same manner as the above-described casing 22.

In accordance with the construction described 15 above, the members 27 which constitute both the bearings for the rolls and portions of the enclosing gas tight casing are arranged at the maximum distance from the source of heat in the furnace whereby they may operate as cool 20 as possible and are also readily accessible and easily detached for inspection and replacement. Inasmuch as the bearing members at the other ends of the rolls are of a similar construction to the members 27 and are secured directly to 25 the furnace, it will be seen that I am able to dispense entirely with the use of stuffing boxes on the rolls and thereby to drive the rolls with a minimum amount of friction loss, yet the gas atmosphere in the furnace is retained without loss 30 around the rolls.

I have chosen the particular embodiment described above as illustrative of my invention and it will be apparent that various modifications 35 may be made without departing from the spirit and scope of my invention which modifications I aim to cover by the appended claims.

What I claim is new and desire to secure by Letters Patent of the United States:

1. A roller hearth furnace constructed to contain a gas atmosphere and having a plurality 40 of rolls extending therethrough, means connected with said rolls for rotating the same and a gas tight casing secured to a wall of the furnace and enclosing corresponding ends of said rolls 45 and said rotating means.

2. A roller hearth furnace constructed to contain a gas atmosphere and having a plurality of rolls extending therethrough, a common means for rotating said rolls and a gas tight casing secured to a wall of the furnace for enclosing 5 said rotating means and the corresponding ends of said rolls.

3. A roller hearth furnace constructed to contain a gas atmosphere and having a plurality of rolls extending therethrough, means connected with said rolls for rotating the same, bearings for said rolls and means for preventing the escape of said atmosphere around said rolls comprising a casing cooperating with said bearings to form a gas-tight enclosure for said rotating 10 means and the corresponding ends of said rolls. 15

4. A roller hearth furnace constructed to contain a gas atmosphere and having a plurality of rolls extending therethrough and having portions 20 extending beyond a wall thereof, a driving member for said rolls connected with said extending portions, means for supporting said rolls and means secured to said wall, and forming a gas 25 tight enclosure for the extending portions of said rolls and said driving member.

5. A roller hearth furnace constructed to contain a gas atmosphere and having a plurality of rolls extending therethrough and having portions 30 extending beyond a wall thereof, a single member connected with the extending portions of said rolls for rotating the same, and a gas tight casing secured to said wall and enclosing said rolls and said member, said casing having bearings secured thereto for said rolls. 35

6. A roller hearth furnace constructed to contain a gas atmosphere and having a plurality of rolls having end portions extending exteriorly 40 of a wall of the furnace, sprockets on said end portions, a drive chain engaging said sprockets, a gas tight casing comprising an enclosure for said portions, sprockets and chain and bearing members for said rolls having closed ends secured to the exterior of said enclosure. 45
